ROTARY PUMP

Ernest H. Shaff, Spring Lake, Mich.

Application May 20, 1947, Serial No. 749,279

2 Claims. (Cl. 103—137)

1

The invention relates to rotary pumps and more particularly to vane type rotary pumps.

One object of the invention is to provide a pump of the above general character which is adapted to deliver a constant flow of fluid substantially free of pulsations.

Another object is to provide a vane type pump characterized by its simplicity of construction, freedom from wear, and high operating efficiency.

Other objects and advantages of the invention will become apparent from the following detailed description of the preferred embodiment illustrated in the accompanying drawing, in which:

Figure 1 is an end elevational view of a pump embodying the features of the invention.

Fig. 2 is a sectional view of the pump taken in a vertical plane substantially on the line 2—2 of Fig. 4.

Fig. 3 is a sectional view of the pump taken in a vertical plane substantially on the line 3—3 of Fig. 4.

Fig. 4 is a sectional view of the pump taken in a vertical plane substantially on the line 4—4 of Fig. 2.

Fig. 5 is a perspective view of the filler block which cooperates with the casing and the rotor to define the pump chamber.

Fig. 6 is a perspective view of the rotor of the pump.

Fig. 7 is a perspective view of the main assembly of the pump.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For purposes of illustration, the invention has been shown as incorporated in a manually operable pump particularly well suited for pumping gasoline or oil. It will be appreciated, however, that the pump may be arranged for power drive if desired, and that it may be used for pumping other liquids, or for compressing air or other gases.

In the preferred form shown, the pump comprises a casing 10 having a pump chamber 11 with two ports 12 and 13 either of which may serve as inlet or outlet ports. Journalized in the casing 10 and eccentrically disposed within the chamber 11 is a rotor 14 carrying a plurality of blades or

5 vanes shiftable generally radially thereof for co-action with the walls of the chamber. When the rotor is turned clockwise, as viewed in Figs. 2 and 3, fluid is drawn through the port 12 into the working portion of the pump chamber and discharged through the port 13, the direction of flow being reversed when the rotor is turned in a counterclockwise direction. As a matter of convenience, it will be assumed that the rotor is normally turned in a clockwise direction and the ports 12 and 13 will be referred to respectively as inlet and outlet ports in the following description of the pump and its mode of operation.

10 In the particular pump shown, the rotor 14 is provided with two vanes 15 and 16 assembled as a unit and slidably received in a recess or slot 17 extending diametrically through the rotor. The vanes 15 and 16 are alike in construction, each comprising a generally rectangular metal block 20 having its outer end portion rounded, as indicated at 18, to provide substantially a line contact with the walls of the pump chamber.

15 As shown in Figs. 1, 2 and 4, the casing 10 is constructed in two sections, including a main section 20 having a cylindrical recess opening at one side and a cover section 22 removably secured to the main section as by screws 22' to close the open end of the recess 21. The pump sections are formed with hollow bosses 23 and 24 opening into the recess 21 through the ports 12 and 13 which are located in the end walls of the recess instead of in the peripheral wall as is customary in pumps of the type under consideration. This arrangement reduces wear on the vanes 15 and 16 and assists in providing a uniform delivery of fluid, as will appear presently. The bosses 23 and 24 are arranged respectively in pairs, each communicating with common ducts or pipes 25 and 26 by which the pump may be connected to the apparatus with which it is to be associated. While the pipes 25 and 26 have been shown as formed integrally with the casing section 20, it will be understood that they may be connected thereto by screw-threaded or other separable connections, if desired.

20 To facilitate manufacture of the pump, the pump chamber 11 is formed by the walls of the recess 21 in cooperation with an arcuate filler block 31 fitted into the recess between the ports 12 and 13. The inner and outer surfaces of the filler block are formed on radii having a common center, the radius of the outer surface being substantially equal to the radius of the recess 21. Accordingly, when the block is installed in the

recess the center of its surfaces coincides with the center of the recess.

The inner surface of the filler block is formed with a radius approximately equal to that of the rotor so as to provide a running fit therewith. The pump chamber is thus defined by opposed arcuate side walls formed on a common center but having different radii. In the exemplary pump these side walls are connected by cam surfaces 32 and 33 formed by beveling the ends of the filler block 31, as shown in Figs. 2, 3, and 5. By mounting the rotor 14 with its axis coincident with the axis of the pump chamber, the working portion of the chamber 11 is thus formed with a uniform cross-sectional area throughout the major portion of its length, the area decreasing abruptly at the ends of the chamber as determined by the slope of the cam surfaces 32 and 33.

Referring now to Figs. 4 and 6 of the drawings, the rotor 14 comprises a cylindrical body having axially projecting shafts 35 and 36 on opposite ends formed integrally therewith or rigidly secured thereto. In the assembled pump structure the shaft 35 is journaled in a bearing cup 37 formed in the end wall of the main casing section 20 and the shaft 36 is journaled in a bearing 38 formed on the cover section 22 of the casing. The latter shaft is arranged to project through the cover section for attachment of suitable driving means, such as a gear or pulley when power drive is contemplated, or for a hand crank 39 when the pump is to be driven manually. A suitable gland 40 is threaded on the outer end of the bearing 38 and provided with the usual packing to prevent leakage around the shaft 36.

As shown in Fig. 6, the end of the shaft 36 is milled to provide opposed flat surfaces 41 for engagement in a generally rectangular aperture in the crank 39 so as to provide a nonrotative connection therebetween. The crank is held in assembled relation with the shaft by a washer 42 (Figs. 1 and 4) and a screw 43 threaded into the end of the shaft. A knob 44 is rotatably mounted on the outer end of the crank 39 for convenient manual manipulation.

As indicated heretofore, the recess or slot 17 extends diametrically through the rotor 14 and, as shown in Fig. 6, it also extends the full length of the rotor. The vanes 15 and 16 are dimensioned to provide a sliding fit with the walls of the slot 17 and of a width such as to provide a working fit with the end walls of the pump chamber 11. Springs 45 interposed between the vanes urge them outwardly into engagement with the arcuate walls of the pump chamber. Accordingly, when the rotor is turned in a clockwise direction, the vanes alternately traverse the chamber 11 and operate in the usual manner to draw fluid into the pump chamber through the port 12 and to discharge it under pressure through the port 14. As each vane moves through the working chamber it displaces a constant volume of fluid until it reaches the cam surface 33 at the end of the chamber. The displacement effected by the vane then decreases as it rides up the cam surface and until the outlet port is opened to receive the fluid trapped in the chamber by the companion vane. As each vane enters the working portion of the pump chamber, it rides down the cam surface 32 at the inlet end of the chamber.

In accordance with the invention, in and out or reciprocating movements of the vanes 15 and 16 are utilized to supplement the delivery of fluid from the working portion of the pump

chamber 11 as the vanes approach the end of the chamber, whereby the fluctuations in delivery or pulsation is eliminated or substantially reduced. More particularly, the vanes 15 and 16 are constructed and the ports 12 and 13 are related thereto in a manner such as to admit fluid into the interior of the slot 17 as either one of the vanes passes the inlet port 12, to momentarily trap the fluid in the recess and to discharge the fluid therefrom through the outlet port 13 as the other one of the vanes passes the latter port. For this purpose each vane is formed with one or more passages 50 extending from the inner end of the vane longitudinally to a point closely adjacent the outer end and then laterally to open at a port 51 in the side wall of the vane. In the exemplary pump each vane is provided with two such passages and the springs 45 are seated therein as shown in Figs. 4 and 7.

To permit the required cooperation between the ports 51, the vanes 15 and 16, and the ports 12 and 13 of the pump chamber, the latter ports are spaced apart slightly less than 180°, that is, closely adjacent but at the same side of a plane passing through the common axis of the rotor and the pump chamber. Accordingly, as each vane rides down the cam surface 32, as shown in Fig. 3, it establishes communication between the port 12 and the interior of the slot 17 by way of the port 51 and passage 50 in the vane. During such outward movement of the vane, the companion vane is held in fixed relation to the rotor by engagement with the walls of the pump chamber 11 and consequently the outward movement of the one vane increases the volumetric capacity of the cavity between the vanes, with the result that fluid is drawn from the inlet port into the recess. The fluid is momentarily trapped in the recess 17 as the first-mentioned vane moves out of registration with the port 12 and before the companion vane registers with the outlet port 13.

In the further rotation of the rotor, the vane which has just passed the inlet port is held in fixed relation with respect to the rotor 14 and the ports 51 of that vane are effectually sealed by end walls of the pump chamber. As the companion vane now rides up on the cam surface 33, it is shifted inwardly of the rotor, thereby decreasing the volumetric capacity of the cavity between the two vanes and forcing the fluid therefrom through the passages 50 of the vane and the ports 51 which register with the outlet port 13. In this way the decreasing discharge from the working portion of the pump chamber 11 is supplemented by the piston-like action of the vanes so that a substantially constant flow of fluid is maintained during the interval in which the respective vanes pass from active to inactive position, and vice versa.

In order to provide a supplemental flow of sufficient volume to eliminate the pulsations in the pump delivery, the vanes 15 and 16 are made relatively thick and the slot 17 is correspondingly dimensioned. The thickness is determined of course by the other dimensions of the pump.

It will be apparent from the foregoing that the invention provides a vane type pump of novel and advantageous character. Through the novel construction of the vanes and their relationship with the other elements of the pump, the normal pump delivery is supplemented by the piston-like action of the vanes so that pulsations are eliminated or substantially reduced and a constant uniform delivery of fluid is effected. The pump is simple

in construction and capable of being manufactured at low cost.

I claim as my invention:

1. In a pump, in combination, a casing having a cylindrical recess therein, inlet and outlet ports, each of said ports being a pair of opposed apertures opening respectively in the opposing end walls of the recess adjacent the peripheral wall thereof, said ports being located on one side of and closely adjacent a plane intersecting the axis of the recess, a rotor mounted in said recess with its axis coincident with the axis of the recess, oppositely projecting vanes disposed within a slot extending diametrically through said rotor and slideable relative thereto for cooperation with the walls of the recess, an arcuate filler block mounted in said recess at the same side of said plane as said ports and defining with the walls of the recess a pump chamber having one wall section engageable with the peripheral wall of the rotor and an opposed wall section spaced therefrom, said vanes in passing over said opposed wall section acting to transfer fluid from said inlet port to said outlet port, and inclined cam surfaces formed on the ends of said filler block, one of said cam surfaces being located adjacent the outlet port and operative to cam the vanes into the rotor in their passage across the outlet port and the other of said cam surfaces being located adjacent the inlet port to permit the projection of the vanes from the rotor in their passage across the inlet port, each of said vanes having opposed lateral apertures adjacent the outer ends thereof and a longitudinal passage extending from said apertures to the inner ends of said vanes so that said vanes are operative in their outward movement to admit fluid from said inlet port into said slot between the vanes and in their inward movement to discharge the fluid from the slot through said outlet port to supplement the discharge of fluid from said pump chamber.

2. A rotary pump comprising, in combination, a casing defining a generally cylindrical recess having closed ends forming opposed end walls and opposed arcuate side walls of different radii formed on a common center and connected by cam surfaces, said casing having inlet and outlet ports opening in said opposed end walls of the recess respectively adjacent said cam surfaces, each of said ports being a pair of opposed apertures opening respectively in said opposed end walls, a cylindrical rotor journaled in said casing with its axis on said common center, said rotor

having a running fit at one side with the wall of shorter radius and being spaced at the opposite side from the wall of longer radius to form there-with a working chamber of substantially uniform cross-sectional area throughout the major portion of its length, said rotor having a slot extending diametrically therethrough, a pair of vanes slidably mounted in said slot to project at opposite sides of the rotor, spring means interposed between said vanes yieldably urging them outwardly against the side walls of the recess, said vanes being operative in the rotation of said rotor to move fluid through said working chamber from said inlet port to said outlet port and having passages operative in the movements of the vanes into and out of said slot as they ride over said cam surfaces to admit fluid to the interior of the slot at said inlet port and to force the fluid from the slot through said outlet port to supplement the discharge from the working chamber of the pump, said ports and said cam surfaces being spaced apart circumferentially of said recess slightly less than one hundred eighty degrees so as to permit a momentary full projection of both vanes simultaneously as one vane passes the inlet ports and the companion vane approaches the outlet port, whereby to increase the volume of the supplemental discharge to a maximum.
